UNITED STATES PATENT OFFICE.

EDWIN NORTON AND JOHN G. HODGSON, OF CHICAGO, ILLINOIS, ASSIGNEES
TO SAID NORTON AND OLIVER W. NORTON, OF SAME PLACE.

MACHINE FOR SEAMING SHEET-METAL CANS.

SPECIFICATION forming part of Letters Patent No. 272,972, dated February 27, 1883.

Application filed September 30, 1882. (No model.)

To all whom it may concern:

Be it known that we, EDWIN NORTON and JOHN G. HODGSON, citizens of the United States, residing in Chicago, in the county of Cook and State of Illinois, have invented a new and useful Improvement in Machines for Seaming Sheet-Metal Cans, of which the following is a specification.

This invention relates to machines for forming double seams on the ends of sheet-metal cans, and its object is to provide a machine for performing this operation automatically and with greater facility and accuracy than heretofore.

In double-seaming machines heretofore in use the seaming-tools are pressed against the revolving can by the hand of the operator, first one tool and then another, or, if only a single tool is employed, first in one position and then in another, for performing the different steps or operations of burring, peening, and finishing the seam, which makes the operation of the machine somewhat slow and tedious, as the attendant must not only place the can upon the revolving stand or chuck, but give it his attention throughout the whole operation. And to do good work and make tight and perfect seams it is necessary that the requisite time should be given to each separate step, and that the tool should be applied to the can with the proper degree of force, so that heretofore it has been necessary to employ skilled labor to run these machines, and even then many imperfect and leaky seams will unavoidably occur.

The present invention consists essentially in the combination, with a revolving chuck for holding and revolving the can, of a seaming tool or tools mounted upon a rocking or movable holder and automatically applied to the can to form the seam by cams or equivalent means, whereby the operation of the machine and its work is rendered uniform and perfect. The revolving chucks or can-holders are mounted upon a turret or table, which is intermittently rotated and locked in position for the can to be operated upon by the seaming-tools. The seaming-tools, consisting of a plain roller, and a bevel-edged roller, are mounted

one above the other on sliding arms, which move radially in and out in suitable slots or guides on a holder secured to a rock-shaft. As the rock-shaft turns up or down stationary cams force the sliding tool-arms in and out and present the tools in different positions to the work, as may be required. Except during the finishing or last step, both tools operate or bear simultaneously upon the work, the one offering an opposing surface for the other to bear against. The tool-holder and cams for operating the tools are all mounted upon an adjustable sliding head, so that the machine may be adjusted to operate upon cans of different sizes.

In the accompanying drawings, which form a part of this specification, Figure 1 is a sectional elevation of a machine embodying our invention. Fig. 2 is a plan view, showing the mechanism for operating the revolving chucks or can holders. Fig. 3 is a detail sectional view of the tool-holding rocker-shaft and the sliding head with the cams removed. Figs. 4, 5, 6, and 7 are views showing the seam in several stages of completion and the positions of the seaming-tools. Fig. 8 is a sectional view, showing the manner of mounting the tool in the tool-holder. Fig. 9 is a plan view of the mechanism for alternately rotating and holding the revolving turret stationary; and Fig. 10 is a detail view, showing the manner of mounting and adjusting one of the cams on the sliding head. Fig. 11 is an enlarged detail side elevation of the seaming-tools, the rock-shaft head or holder in which they are mounted so as to reciprocate therein, and the stationary but adjustable cams for imparting to the seaming-tools their reciprocating or sliding motion as the head or holder in which they are mounted is rocked up and down.

In the drawings similar letters of reference indicate like parts throughout the several figures.

A is the frame of the machine, and B is the revolving turret, secured to the hollow sleeve C, which is journaled in suitable bearings, C' and C'', on the main frame of the machine. The turret-arms B' are provided with chuck or can-holding disks b b', mounted to revolve with the

small shafts b^2 b^3 , the lower disks, b , being raised, so as to clasp the can between it and the upper one, by means of the cams e and levers c' , and rotary motion being communicated to the upper disk, b' , so as to revolve the cans, by means of the gears b^4 on the shafts b^3 meshing with the gear-wheel a on the central shaft, a' , which is driven by the pulley a^2 . The lower turret-wheel, B , may be adjusted to different heights 10 on the sleeve C by means of the set-screw a^3 , so as to accommodate the chucks or can-holders to cans of different heights.

D is a rock-shaft journaled in a suitable bearing, D' , on the sliding head G , and to the 15 end of the shaft the tool-holder or head d is secured so as to rotate or rock with it. The tool-holder d is provided with radial grooves or guides, in which the arms or slides, d^2 on which the seaming-tools d^3 d^4 are journaled, 20 may move in and out to or from the work. The sliding arms d^2 are actuated, as the tool-holder is rocked or rotated, by means of stationary grooved cams E and E' , the arms d^2 being provided with pins e , which fit in said 25 grooved cams. The pins e should be provided with small friction pulleys or rolls. The shaft D is rocked about a quarter-turn on its axis by means of the crank-arm D^6 and the pitman D^2 , connected to the revolving wheel 30 D^3 on the shaft D^4 , which is driven by the pulley D^5 . The sliding head G , to which the cams E and E' are secured, and upon which the rock-shaft is mounted, may be moved in and out upon its support H' to adjust the machine 35 to different-sized cans by means of the adjusting-screw H . The upper cam E is pivoted at its upper end to the sliding head G , and is provided with an independent adjusting-screw h at its lower end, whereby the force 40 with which the finishing-roll presses against the can may be regulated. The cam E' is secured to the sliding head G by screws or bolts e' passing through a flange, e^2 , on the cam E' .

The turret is rotated by means of a pitman, 45 K , spring-ratchet k , which engages with the ratchet-wheel k' , and the turret is locked in position by means of the spring-bolt k^2 , which engages with notches k^3 in the chuck-wheel k^4 . The spring-bolt k^2 is withdrawn, to permit the 50 wheel to revolve, by means of a projection or lip, k^5 , on the pitman-rod. The pitman-rod K is connected by a wrist-pin to the wheel k' on the shaft D^4 .

k^2 is a clutch, whereby the mechanism for 55 operating the seaming-tools and turret is thrown in and out of gear.

The operation of the seaming-tools is as follows: A can and its head or cover being placed in one of the chucks of the turret and the turret revolved into the position shown in Fig. 1, the revolution of the pitman-wheel D^3 rocks the shaft D , causing the cam E' to force the bevel-roller or peening-tool against the flange of the cover and fold it over the flange on the 60 can-body, as shown in Fig. 5, and at the same time the cam E presses the smooth or finish-

ing tool down on the top edge of the cover, so as to hold the same on and afford an opposing surface for the peening-tool to bear against. As the tool-holder swings down on the curve 70 the cams hold both tools against the seam until it assumes the form shown in Fig. 6, the peening-roller offering a support to the under side of the seam, while the smooth roller above is turning the seam down. As the tool-holder 75 swings still farther down to the end of its stroke the cam E' draws back the bevel peening-tool, while the smooth roller, assuming a horizontal position, finishes the seam and presses it smooth against the side of the can. 80 The seaming-tools, it will thus be seen, have a compound swivel or rotary and reciprocating motion, the swivel or rotary motion being communicated to the tools by the swinging or rocking of the tool-holder on the rock-shaft, 85 and the reciprocating motion of the tools on the tool-holder being due to the action of the cams on the sliding tool-arms.

The point or edge of the bevel peening-roller d^4 , as shown in Figs. 1, 5, and 6, is the center 90 or axis of the rock-shaft, and the circular or middle portion of the cam E' is an arc of a circle about such center, so that the peening-tool swings around such point as a center until it is withdrawn by the lower or upper portions 95 of the cam.

We have shown in the drawings what we consider the best method of practicing our invention and the preferable number and form of seaming-tools to be used, as well as what 100 we believe to be the most desirable means or mechanism for actuating the same; but the particular number and form of the seaming-tools may be greatly varied, as well as the particular form of the mechanism for actuating 105 the same, without departing from the essential feature or principle of our machine or invention.

M is a stationary cam-ring for automatically 110 raising the lower disk of the chuck as the turret is revolved to clasp the can and hold it firmly while being operated upon by the seaming-tools. The raised portion of the cam is about one-third the circumference of the cam-ring. 115

We claim—

1. The combination of a revolving can-holder or chuck with a rocking or swiveling tool-holder and seaming-tools mounted in said holder and reciprocating radially therein, and means for automatically actuating said tool-holder and tools, substantially as specified. 120

2. The combination, with a rocking tool-holder provided with seaming-tools reciprocating thereon, of means for operating said 125 tool-holder and tools, and an intermittently-rotating turret provided with revolving chucks for the cans, substantially as specified.

3. The combination of a revolving can-holder or chuck with a tool-holder secured to a rock-shaft, and seaming-tool mounted movably on 130 said holder, and a cam for operating said tool

as the shaft is rocked, substantially as specified.

4. In a can-seaming machine, the combination of a revolving chuck or holder for the can with a seaming-tool journaled on a sliding arm, and a rocking tool-holder in which said arm is mounted, and a cam for operating the sliding arm as the tool-holder is rocked, substantially as specified.
5. The combination, with a revolving chuck for the can, of a tool-holder secured to a rock-shaft and provided with radial grooves or guides, sliding tool-arms mounted in said grooves, a finishing and a bevel-edged tool journaled on said arms, and stationary cams for operating said tools, substantially as specified.

6. The combination of a revolving turret, mechanism for alternately revolving and locking the turret in position, revolving chucks for the cans mounted on said turret, with an adjustable sliding head and seaming-tools, and means for operating the seaming-tools mounted on said head, substantially as specified. 20

7. The combination of the seaming-tools with a tool-holder, rock-shaft, pitman-rod for operating said rock-shaft, and cams for actuating the seaming-tools, substantially as specified. 25
